UNITED STATES PATENT OFFICE

149,261

DESIGN FOR A HOLDER FOR A CYLINDRICAL FIRE EXTINGUISHER OR SIMILAR ARTICLE

Armand De Mott, Fords, N. J., assignor to Amity Manufacturing Corp., Perth Amboy, N. J., a corporation of New Jersey

Application October 2, 1946, Serial No. 133,695

Term of patent 14 years

(Cl. D16—2)

To all whom it may concern:

Be it known that I, Armand De Mott, a citizen of the United States, residing in Fords, county of Middlesex, and State of New Jersey, have invented a new, original, and ornamental Design for a Holder for a Cylindrical Fire Extinguisher or Similar Article, of which the following is a specification, reference being had to the accompanying drawing, forming a part thereof.

Fig. 1 is a perspective view of a holder for a cylindrical fire extinguisher or similar article embodying my new design, and

Fig. 2 is a front elevational view thereof.

I claim:

The ornamental design for a holder for a cylindrical fire extinguisher or similar article, as shown.

ARMAND De MOTT.
